UNITED STATES PATENT OFFICE.

WILLIAM G. WALL, OF INDIANAPOLIS, INDIANA, ASSIGNOR TO NATIONAL MOTOR CAR & VEHICLE CORPORATION, OF INDIANAPOLIS, INDIANA, A CORPORATION OF NEW YORK.

BODY CONSTRUCTION.

1,395,538.

Specification of Letters Patent.

Patented Nov. 1, 1921.

Application filed June 5, 1920. Serial No. 386,787.

To all whom it may concern:

Be it known that I, WILLIAM G. WALL, a citizen of the United States, residing at Indianapolis, in the county of Marion and State of Indiana, have invented certain new and useful Improvements in Body Construction, of which the following is a specification.

This invention relates to body construction, more especially to the mounting of the automobile body upon the frame of the car. Hitherto the body of the car was mounted on the top of the frame which consists of longitudinal channel or similar bars and cross bars securing the same rigidly together. Such body construction is comparatively weak and causes the body to sit high on the frame, it being among the objects of this invention to obviate such disadvantages and produce a structure which is simple, rigid, and allows the body to be mounted in a lower position.

In carrying the objects of my invention into effect, I provide the ordinary metal frame and form the base of the body of beams, preferably wooden, set on edge. The body is so placed on the frame that the beams pass to the outside of the channel bars and parallel with the outer faces of the bars and are held in place by brackets on the frame or by other suitable means.

Referring to the accompanying drawings forming a part hereof and in which similar reference characters denote similar parts. The single figure illustrates a perspective view of a portion of an automobile body embodying my invention some parts being shown in section for clearness.

The longitudinal channel bars 1 of the frame have brackets 2 secured by bolts 3 to the lower portion thereof. The horizontal shelves 4 of brackets 2 are a substantial distance below the top 5 of the channel bars.

The base of the body includes longitudinal beams 6 and 7 usually made of wood, which are set on edge, as shown and rest on the shelves 4 of brackets 2. Members 7 are secured to the beams 6 and project a distance above the upper edges of beams 6 and floor 8 of the body proper is secured in members 7 resting in depressions 9 formed in the upper edge thereof, so as to leave a space 10 between

the bottom of the floor and the top 5 of the channel bars. The foot board 11 is attached to the body through mud guard 12 and sheathing 13 is secured to the outside of the body, the sheathing having its lower end looped and overhanging the top of mud guards or running board splashes 12.

By placing the beams 6 on edge I form a more rigid body base with the use of no larger timbers than hitherto, and I am enabled to lower the body considerably, due to the body base being fitted over and on the outside of the frame. It is obvious that various changes in the details of construction, such as the omission of beams 7 and allowing the floor to rest directly on bars 4, may be made in the structure described within the scope of my invention.

Having thus fully described my said invention, what I claim as new and desire to secure by Letters Patent, is:

1. In a body construction a frame, brackets secured to the outer face of said frame and having their top surface a substantial distance below the top of the frame, a body base supported by the brackets and extending above the frame, and a floor supported by the body base at such a point as to overhang and be spaced above the frame, substantially as set forth.

2. In a body construction a frame, a body base, brackets secured to the outer face of said frame upon which said base rests, a floor secured to said base, said floor being a substantial distance above the top of said frame, said base comprising beams, said beams being set on edge, and sheathing and mud guards secured to said base.

3. In a body construction a frame, a body base fitted along the outer face of and parallel with said frame, mud guards secured to said base, and sheathing also secured to said base, said sheathing overhanging the top of said guards.

In witness whereof, I have hereunto set my hand and seal at Indianapolis, Indiana, this 2nd day of June, A. D. nineteen hundred and twenty.

WILLIAM G. WALL. [L. S.]
